UNITED STATES PATENT OFFICE

CHARLES V. MCINTIRE, OF FAIRMONT, WEST VIRGINIA, ASSIGNOR TO CONSOLIDATION COAL PRODUCTS COMPANY, OF WILMINGTON, DELAWARE, A CORPORATION OF DELAWARE

APPARATUS FOR CHARGING AND DISCHARGING CARBONIZING OVENS FOR FUEL BRIQUETTES

Application filed June 12, 1926. Serial No. 115,435.

This invention relates to apparatus for carbonizing coal, particularly designed for carbonizing the fuel briquettes described and claimed in my copending application Serial No. 112,497, filed May 29, 1926.

In carbonizing fuel briquettes in retorts of the type illustrated in Smith Patent No. 1,409,597 it is the practice to charge the raw briquettes into the hot ovens. In my experience I have found this practice disadvantageous for two reasons: first, when the briquettes come in contact with the hot walls of the ovens the rapid evolution of gas usually causes them to split open, and, second the briquettes next to the walls are coked much more rapidly than those in the interior of the ovens, thus necessitating a long, detrimental soaking heat for the former to effect the desired carbonization of the latter. In accordance with the present invention I place the briquettes in thin layers upon a perforate support spaced from the walls of the ovens so that they do not come in contact with the walls but are heated uniformly by radiant heat.

For ease in handling I prefer to make the supports for the briquettes in the form of removable trays and in accordance with the present invention have provided mechanism for moving these trays into the ovens and withdrawing them after carbonization. Associated with this charging and discharging mechanism, I have provided means for depositing a layer of briquettes upon the trays as they are moved into the ovens and means for dumping the trays and quenching the briquettes after carbonization. The trays are dumped before quenching to conserve their heat. I prefer to employ a retort comprising a bench of superposed ovens. For this reason I mount my charging and discharging mechanism on a vertically movable cage which can be raised and lowered to operate in connection with any one of the vertically disposed ovens.

In the accompanying drawings which illustrate a preferred embodiment of my invention, Figure 1 is a side view partly in section taken along line 1—1 of Figure 2 showing the carbonizing retort and the mechanism for feeding, discharging and quenching; Fig-

ure 2 is a view also partly in section taken along line 2—2 of Figure 1 and Figure 3 is an enlarged transverse sectional detail through one of the ovens taken along line 3—3 of Figure 1; Figure 4 is a plan view taken along line 1—1 of Figure 1 and Figures 5, 6 and 7 are transverse sectional details taken along lines 5—5, 6—6 and 7—7 respectively of Figure 4.

In these drawings 1 represents a carbonizing retort comprising a bench of horizontal superposed muffle ovens 2 which are heated from above and below by means of transverse heat flues 3 to which gas and air are fed by conduits 4 and 5 respectively and from which the products of combustion are removed through waste heat flues 6. The briquettes 7 are supported within the oven upon a train of coupled trays 8 provided with perforate bottoms 9 made of some heat-resistant screen cloth. The trays are provided with longitudinal flanges 11 which are received and supported by longitudinal slides or tracks 12 on the side walls of the oven. The briquettes are placed upon the trays in thin layers two rows deep, and the trays so loaded support the briquettes substantially midway between the floor and roof of the oven. I shall now describe the mechanism by which the ovens are charged and discharged and the briquettes quenched.

Mounted adjacent the front of the retort is a tower 13 which carries at its upper end a fixed bin and feed hopper 14 to which raw briquettes are conveyed from the briquetting presses by means of a belt conveyor 15. At one side of the hopper 14 and immediately in front of the ovens a cage 16 is mounted in guideways 17 for vertical movement, and raised and lowered by means of a winding drum 18 mounted on the upper frame of the tower, cable 19 and sheaves 20. This cage carries mechanism for moving the trays into and out of the oven, means for feeding briquettes to the trays as they are moved into the oven, and means for quenching the carbonized products.

The cage supports the trays upon tracks 22 provided with double flanged guides 23 which receive the flanges 11 on the trays. Likewise

mounted upon this track 22 is a ram or puller 24 provided with a coupler 25 designed to connect with the rear member of a train of trays. An endless cable 26 extends along the track 22, about idler sheaves 27 and around winding drum 28 and is fastened at 29 to the under side of the ram 24. When the guides 23 of the track 22 are in registry with the slides 12 of one of the ovens the trays can be moved into and out of that oven by proper manipulation of the winding drum 28.

On its oven side and immediately above the track 22 the cage carries a movable feed hopper 31 which receives raw briquettes from the bin 14. The lower and discharge end of this feed hopper 31 is closed by means of a shaker plate 32 swingingly supported by means of four suspension arms 33. The side wall of the hopper 31 nearest the oven terminates a sufficient distance above the plate to permit the passage of briquettes. A horizontal reciprocation of the shaker plate in the line of travel of the trays is effected by means of a crank 34 driven by means of a worm wheel 35, connecting rod 36 and lever 37 depending from the tray and forming, in effect, an extension of the suspension arms. As the trays are moved into an oven raw briquettes are deposited upon them by means of the shaker feed mechanism just described, the reciprocating plate causing the raw briquettes to move out of the hopper onto the plate, and thence off its outer end onto the trays passing beneath.

After the briquettes have been carbonized the trays are withdrawn by means of the ram 24. Both briquettes and trays are then in a very highly heated condition and before the briquettes can be handled they must be quenched. I shall now describe the means by which I accomplish this.

An intermediate section 38 of the track 22 of a length equal to the train of trays is discontinuous with the end sections and is pivotally mounted at 39 about its longitudinal axis, thus forming a tipple. Immediately below this tipple is a bin 41 terminating at one side in a water bath 42 and at the other in a discharge hopper 43. Pivotally mounted at 44 upon the longitudinal dividing wall 45 between the water bath and the discharge hopper is a basket 46 in the shape of a cylindrical segment, the arcuate side wall and that portion of the bottom on the water bath side of the pivot being perforate, while the ends and that portion of the bottom on the discharge hopper side of the pivot are imperforate. The basket is raised and lowered about the pivot by means of cables 47 passing around winding drums 48 on a shaft 49 rotated by means of worm set 50. The water bath is provided with a sluice valve 51 for the removal of dirt or braize.

When a set of trays is to be dumped the basket is submerged in the water bath, as il-

lustrated in Figure 2, and the tipple section 38 of the track manually rotated about its longitudinal axis until it and the trays assume the dotted line position shown in Figure 2, thus discharging the carbonized briquettes into the basket and the water bath. The trays are retained in the tipple by means of the double flanges 23 of the guide. In order to facilitate the return of the tipple to its normal position and to retain it in that position during longitudinal movement of the trays, the tipple is provided with two depending counterweights 52. When the tipple has returned to its normal horizontal position the trays, still in their highly heated and unquenched condition, are in readiness for receiving a new charge, and may be returned to the empty oven, first however being loaded with briquettes as they pass under the feed hopper 31.

The quenched briquettes in the submerged basket are now ready for discharging. By means of the worm set 50, winding drums 48, and cables 47, the basket is swung into the elevated position illustrated in dotted lines in Figure 2 and the briquettes discharged into the hopper 43, the lower end of which hopper is normally closed by means of a swing counterweighted door 53. From this hopper the briquettes are discharged into a wharf 54 and thence onto a belt conveyor 55.

The vertical travel of the cage is sufficient to permit alignment of the track 22 with the tracks 12 of the several ovens. I also preferably place a series of racks 56 for spare trays on the top of the bench and therefore increase the range of movement of the cage sufficiently to permit the utilization of these racks. It will be observed from a study of Figure 2 that briquettes cannot be fed from the fixed bin 14 to the hopper 31 when the cage is above the position illustrated in Figure 2, and that carbonized briquettes cannot be discharged from the hopper 43 to the wharf 54 when the cage is below the position illustrated in Figure 2. It is to be understood, of course, that the hopper 31 is loaded when in proper relation with hopper 14 and carries sufficient briquettes to supply all of the ovens at least once. The same is true of hopper 43 so that the discharge of briquettes from this hopper to the wharf need be effected only periodically and when the cage is in proper position.

I claim:

1. Apparatus for charging fuel briquettes into a carbonizing oven comprising the combination of a tray for the briquettes, means for moving the tray into the oven, a hopper for raw briquettes, a receiving plate immediately below the discharge end of the hopper and above the top surface of the tray, and means for reciprocating the plate to deposit a layer of briquettes upon the tray as it is moved into the oven.

2. Apparatus for charging fuel briquettes

- into a carbonizing oven and discharging them therefrom comprising the combination of a tray for the briquettes, and an external track in alignment with a track within the oven for supporting the tray, a section of the external track being pivotally mounted to permit dumping of the tray. 3. Apparatus for charging fuel briquettes into a carbonizing oven and discharging them therefrom comprising the combination of a tray for the briquettes, means for moving the tray into and out of the oven, a track in alignment with the oven for supporting the tray outside the oven, a section of the track being pivotally mounted to form a tipple for dumping the tray, a water bath below the tipple, and a perforate basket within the water bath. 4. Apparatus for charging fuel briquettes into a carbonizing oven and discharging them therefrom comprising the combination of a tray for the briquettes, means for moving the tray into and out of the oven, a track in alignment with the oven for supporting the tray outside the oven, a section of the track being pivotally mounted to form a tipple for dumping the tray, a water bath below the tipple, a perforate basket within the water bath, and means for dumping the basket. 5. Apparatus for charging fuel briquettes into a carbonizing oven and discharging them therefrom comprising the combination of a tray for the briquettes, means for moving the tray into and out of the oven, a track in alignment with the oven for supporting the tray outside the oven, a section of the track being pivotally mounted to form a tipple for dumping the tray, a water bath below the tipple, a hopper adjacent the water bath, a perforate basket pivotally mounted between the water bath and the hopper, and means for lowering the basket into the water bath and for dumping the basket to discharge the quenched briquettes into the hopper. 6. Apparatus for charging fuel briquettes into a carbonizing oven and discharging them therefrom comprising the combination of a tray for the briquettes, means for moving the tray into and out of the oven, a hopper for raw briquettes, means for depositing a layer of briquettes from the hopper upon the tray as the latter is moved into the oven, and an external track in alignment with a track within the oven for supporting the tray, a section of the external track being pivotally mounted forming a tipple to permit dumping of the tray, and a water bath below the tipple for quenching the carbonized briquettes. 7. Apparatus for charging fuel briquettes into a carbonizing retort having a plurality of vertically arranged horizontal ovens and for discharging the carbonized briquettes therefrom comprising the combination of trays for the briquettes movable into and out of the ovens, a tower positioned in front of the ovens, a cage mounted in the tower for vertical movement, a track on the cage for supporting the trays externally of the ovens, means for moving the cage to align the track with any oven and means for moving the trays into and out of the ovens. 8. Apparatus for charging fuel briquettes into a carbonizing retort having a plurality of vertically arranged horizontal ovens and for discharging the carbonized briquettes therefrom comprising the combination of trays for the briquettes movable into and out of the ovens, a tower positioned in front of the ovens, a cage mounted in the tower for vertical movement, a track on the cage for supporting the trays externally of the ovens, means for moving the cage to align the track with any oven, a hopper for raw briquettes carried by the cage, means for moving the trays into the ovens, and means for depositing a layer of briquettes from the hopper upon the trays as they are moved into the ovens. 9. Apparatus for charging fuel briquettes into a carbonizing retort having a plurality of vertically arranged horizontal ovens and for discharging the carbonized briquettes therefrom comprising the combination of trays for the briquettes movable into and out of the ovens, a tower positioned in front of the ovens, a cage mounted in the tower for vertical movement, a track on the cage for supporting the trays externally of the ovens, a section of the track being pivotally mounted to form a tipple to permit dumping of the trays, and means for moving the cage to align the track with any oven. 10. Apparatus for charging fuel briquettes into a carbonizing retort having a plurality of vertically arranged horizontal ovens and for discharging the carbonized briquettes therefrom comprising the combination of trays for the briquettes movable into and out of the ovens, a tower positioned in front of the ovens, a cage mounted in the tower for vertical movement, a track on the cage for supporting the trays externally of the ovens, a section of the track being pivotally mounted to form a tipple to permit dumping of the tray, a water bath carried by the cage below the tipple, a perforate basket within the water bath, and means for moving the cage to align the track with any oven. 11. Apparatus for charging fuel briquettes into a carbonizing retort having a plurality of vertically arranged horizontal ovens and for discharging the carbonized briquettes therefrom comprising the combination of trays for the briquettes movable into and out of the ovens, a tower positioned in front of the ovens, a cage mounted in the tower for vertical movement, a track on the cage for supporting the trays externally of the ovens,

means for moving the cage to align the track with any oven, means carried by the cage for moving the trays into and out of the ovens, a hopper carried by the cage for feeding briquettes to the trays as they are moved into the ovens, a tipple section in the track permitting dumping of the trays, a water bath carried by the cage below the tipple, a hopper carried by the cage adjacent the water bath, and means for transferring the quenched briquettes from the water to the hopper.

12. Apparatus for charging fuel briquettes into a carbonizing retort having a plurality of vertically arranged horizontal ovens and for discharging the carbonized briquettes therefrom comprising the combination of trays for the briquettes movable into and out of the ovens, a tower positioned in front of the ovens, a cage mounted in the tower for vertical movement, a track on the cage for supporting the trays externally of the ovens, means for moving the cage to align the track with any oven, means carried by the cage for moving the trays into and out of the ovens, a hopper carried by the cage for feeding briquettes to the trays as they are moved into the ovens, a tipple section in the track permitting dumping of the trays, a water bath carried by the cage below the tipple, a hopper carried by the cage adjacent the water bath, means for transferring the quenched briquettes from the water bath to the hopper, a fixed hopper on the tower for feeding raw briquettes to the movable feed hopper on the cage and a fixed receptacle on the tower for receiving carbonized briquettes from the movable discharge hopper on the cage.

40 In testimony whereof I affix my signature.
CHARLES V. McINTIRE.
